ABSTRACT OF THE DISCLOSURE

A pump has a control element mounted within its pump housing. On this control element is mounted sealing means to seal the inlet and the outlet of the housing. The control element furthermore has passages for directing fluid within the housing to and from the pump impeller. The control element is adjustable between a position in which the inlet and outlet openings are sealed closed and a position in which these openings are in communication with the pump impeller.

The invention relates to a controllable liquid conveying assembly having an axially divisible housing whose component parts are designated in the following as pump housing and motor block housing, as well as a control element actuatable externally for controlling the conveying liquid radially flowing to and discharging from the pump housing.

The objects of the invention are:

To provide a liquid conveying assembly which permits the conveyance of liquids having a relatively high content of foreign bodies, in an unfiltered state, or which can be placed in operation again without difficulty even after long intervals of inoperativeness, such as, for example, a pump for hot water heaters with forced cycle.

To provide an assembly of the type mentioned having means to free rapidly critical parts of the assembly from foreign bodies and, if required, to quickly exchange those parts.

To provide a controllable liquid conveying assembly of the above-described type wherein the control element is provided with sealing elements permitting the sealing of the pump housing in a liquid-tight manner, and wherein the pump impeller is combined structurally with the rotor of an axial electric motor, without the use of glands or stuffing boxes.

To provide an assembly of the type mentioned including means separating the pump housing from the conveying liquid cycle and to reach the axially divisible housing after the control element is brought into its closed position, whereby after opening of the assembly it is possible simply to disassemble in dry state the stator of the axial motor, and also the structural unit formed by the pump impeller and the rotor of the motor and without difficulty to exchange it or to clean it, and then to reassemble it.

To provide the assembly of the invention with liquid inlet and outlet openings of the pump housing enclosed, in the closed position of the control element, preferably by one sealing element positioned in a sealing manner between the housing and the control element.

To provide the assembly of the invention with a particularly simple, compact structure by positioning the control element rotatably and coaxially to the pump motor axis and by giving this control element an outer surface movable as a seal in front of the liquid inlet and outlet openings.

Other objects and many of the attendant advantages of this invention will be readily appreciated as the same

2

becomes better understood by reference to the following detailed description when considered in connection with the accompanying drawing in which like reference numerals designate like parts throughout the figures thereof and wherein:

FIGURE 1 is a partially cross-sectioned, longitudinal view of a controllable liquid conveying assembly according to the invention.

FIGURE 2 illustrates, on a larger scale, a partial view of the arrangement of FIGURE 1 showing in detail the construction of the conical bearing for the unit formed by the motor rotor and the pump impeller.

FIGURE 3 is a view of the pump housing and the control element shown in the direction of arrow A of FIGURE 1, after the motor block housing has been removed, together with the unit formed by the motor rotor and the pump impeller, the control element being illustrated in the closed position.

FIGURE 4 is a view of the control element in the direction of arrow B of FIGURE 3.

FIGURE 5 shows, on a larger scale, a partial cross section through a modified embodiment of the invention wherein the control element is axially displaceable and connectible with the pump impeller; and

FIGURE 6 shows a section along line VI—VI of FIGURE 5.

The liquid conveying assembly of FIGURES 1—4 is provided with an axially divisible housing having a pump housing 1 and a motor block housing 2.

The stator of the axial motor mounted in the motor block housing is provided with an annular magnetic iron core 3, and excitation windings 4 supplied with current from the mains. A screw bolt 7 is threadedly inserted into an axial bore 5 of a central boss 6 of the motor block housing 2. A membrane 8 seals the motor block housing on the side facing the pump housing 1, in a fluid-tight manner; a seal 10 inserted in an annular body 9 sealingly engages the central, smooth section 11 of the screw bolt 7 and the membrane 8. An insulating cast mass 12, for example of synthetic resin or silicone rubber, filled in after the membrane 8 has been mounted at the motor block housing, supports the membrane against the fluid pressure of the rotor chamber and simultaneously protects the stator windings.

An axle 15 is threaded onto the end of the screw bolt 7 facing away from the boss 6 of the motor block housing. The axle carries a shaft box 16 on the side facing the motor block housing on which the rotor of the axial motor, having an annular magnetic iron core 17 and a squirrel cage winding 18, is positioned. The pump impeller 19 is fixedly connected with the rotor 17, 18 of the axial motor, for example by a threaded connection. The impeller 19 is a centrifugal impeller and has open vanes 20. The boss 21 of the impeller carries a bearing ring 22, seen in FIG. 2, which forms a conical bearing together with a cone-shaped bearing part 23 inserted into the end of the axle, facing away from the motor block housing. The bearing ring 22 and the bearing part 23 are made of hard metal or other material resistant to wear and tear.

In operation, the magnetic forces effective between the stator 3, 4 and the rotor 17, 18 of the axial motor attempt to pull the rotor against the stator. These forces are absorbed by the conical bearing 22, 23 effective as an axial bearing, while the axle, together with the shaft box 16 rotatably mounted thereon, forms a radial bearing for the structural unit formed by the motor rotor 17, 18 and the pump impeller 19.

An annular flange 25 of the motor block housing encompasses the open end of the pump housing facing the motor block housing. Screws 26 which extend through radial flanged portions of the motor block housing and which are threaded into threaded bores 27 of lugs 28 of

the pump housing as seen in FIG. 3, hold the housing parts 1, 2 together in a detachable fashion. In this connection, a sealing ring 29 inserted between the front edge of the pump housing and the membrane establishes a fluid-tight connection of the two housing portions 1, 2.

The pump housing has radial connecting studs 32, 33 which oppose each other diametrically. In the front wall 34 of the pump housing, facing away from the motor block housing is rotatably mounted the boss 35 of the control element 36. A handwheel 39 having the shape of a disk and being provided with grip-type teeth 38 is mounted by screws 37 at the end of the boss 35 extending beyond the front wall 34 to the outside. A cup spring 40 pushed onto the boss abuts against the outer surface of the front wall 34 and the front edge of the boss 41 of the handwheel 39. The spring 40 attempts to press the control element 36 against the front wall 34 so that the shoulder 42 of the control element engages the sealing ring 43 and the inner surface of the front wall 34. A sealing ring 44 held in an annular groove in the boss 35 presses against the wall of the bore of the front wall 34 receiving the boss 35. The boss 35 and the handwheel 39 have central bores which are in alignment with one another. A locking screw 45 with a sealing ring 46 is passed through the central bore of the handwheel 39 and is threaded into the central bore of the boss 35.

The control element 36 has a cylindrical outer surface 48 slidingly fitting into the bore of the pump housing. Flat, circular recesses 50, 51 of the outer surface 48, which oppose each other diametrically, serve for receiving sealing rings 52 which encompass in a sealing manner the bores of the connecting lugs 32, 33 in the closed position of the control element 36 illustrated in FIGURES 1 and 3, and thus separate the pump housing 1 in a fluid-tight manner from the liquid cycle connected to the studs 32, 33.

As seen from FIGS. 3 and 4, the outer surface 48 of the control element is provided with a stepped liquid inlet opening 53 and the control element on the side of the impeller is provided with two tongue-shaped guide flanks 54, 55. The guide flanks 54, 55 form an acute angle with the tangent on the circumference of the control element 36, this angle being preferably between 60° and 75°. The mutual distance of the guide flanks 54, 55 corresponds, at the periphery of the control element 36, approximately to the width of the opening of the connecting pipes 32, 33 in the direction of their circumference.

By turning the control element 36 from the closed position according to FIGURE 3 in counter-clockwise direction, there is first brought into congruence with the bore of the connecting pipe 32 the smaller cross-sectional area 64, and then the larger cross-sectional area 65 of the inlet opening 53 of the control element. Thus, progressively larger amounts of conveying liquid can flow through the pipe 32 into the pump housing. The liquid enters the hollow space 57 on the inlet low-pressure side of the control element 36; this hollow space is hydraulically connected through openings 58 of the control element, with the hollow space 59 on the inlet side of the pump impeller 19. From there, the liquid is forced into the hollow space 60 on the outlet high-pressure side of the impeller 19 and leaves the pump housing through the now open bore of the connecting pipe 33. By turning the control element 36 by 180°, the conveying direction of the pump can be reversed in a simple manner, the connecting pipes 32, 33 reversing their respective functions.

In order to cool, during operation, the radial bearing formed by the axle 15 and the shaft box 16, and in order to lubricate same with conveying liquid, the shaft box 16 is provided with lubricating grooves which are not shown, and which run in the axial direction. These lubricating grooves are hydraulically connected, via radial channels 61 of the motor rotor 17, 18, with the high-pressure chamber 60. Upon rotation of the rotor, conveying liquid is constantly fed to the lubricating grooves. At 75

the same time, the conical bearing 22, 23 is lubricated by an axial bore 62 of the impeller boss 21. An annular protective shell 70 located on the membrane 8 prevents the flushing of larger particles of dirt into the channels 61, the motor air gap, and the bearing slots.

When the pump impeller 19 adheres tightly to the axle 15, for example, after a longer operating pause, and cannot be detached by the starting torque of the axial motor, the control element 36 is placed in its closed position. If then the locking screw 45 is removed, a screw driver can be inserted through the aligned central bores of the handwheel 39 and the hub 35 of the control element 36, and can be brought into engagement with the groove 63 on the free front side of the boss 21 of the pump impeller 19, in order to free the pump impeller by hand.

When the air gap of the motor and the bearing surfaces are to be cleaned, or other parts of the assembly are to be checked or replaced, the pump housing 1 is again blocked against the liquid cycle with the aid of the control element 36. Then, the screws 26 are loosened, whereby the motor block housing 2, along with the unit formed by the motor rotor 17, 18 and the pump impeller 19, can be removed. The motor rotor and the pump impeller can be pulled off the axle 15 with one grip.

The embodiment of the invention illustrated in FIGURES 5 and 6 differs from the previously described embodiment only in that measures are provided for de-blocking the assembly. For this purpose, the control element 36 is mounted, with its boss 35 in the front wall 34 of the pump housing 1, against the force of the cup springs 40, in an axially displaceable manner. A tappet-follower 68 with a tappet nose 69 is fixedly inserted in the front face of the box 35 facing the pump impeller 19. The opposite front face of the boss 21 of the pump impeller 19 is provided with a groove 67 suitable for receiving the tappet nose 69.

In order to de-block the pump impeller 19, the control element 36 is displaced axially toward the inside by means of pressure exerted upon the handwheel, and, if required, rotated at the same time until the tappet nose 69 engages the groove 67. By subsequently turning the handwheel 69 even further, the blocked pump impeller is loosened.

Thus, the motor rotor is provided advantageously with radial channels which are in communication with, on the one hand, the bearing slot space on the low-pressure side and, on the other hand, the outer rotor space on the high-pressure side. Through the radial channels, with the rotor rotating, a flow of liquid is constantly maintained which cools and lubricates the bearings of the unit formed by the motor rotor and the pump impeller.

By actuating a single component part—the control element—flow of the conveying liquid through the inlet and outlet openings can be throttled. By fashioning the outer surface of the control element, which sealingly engages, in the closed position of the control element, the liquid inlet and outlet openings, to be cylindrical, it is avoided that a fluid pressure which might be ambient in the pump inlet line exerts an axial impetus upon the control element which was placed in its closed position, which axial impetus can lead to undesired problems in the mounting and sealing of the assembly. Moreover, because of the use of an axial motor, a conveying assembly can be provided having a total relatively short axial structural length not considering the axial space required for the control element.

The radial inlet and outlet openings of the pump housing are preferably positioned diametrically opposite to one another, so that the direction of flow of the conveying liquid through the pump can be reversed by turning the control element by 180°.

The pump housing can be provided, for the feeding and discharging of liquid, with several openings, for example, two inlets and one common outlet, which all cooperate with the control element. In this manner, the conventional

mixing effects for several conveying liquid cycles can be obtained.

In a further development of the invention described above, the unit formed by motor rotor and pump impeller is furthermore mounted on a fixed axle connected with the motor block housing and is rotatable; this fixed axle, in addition to being a radial mounting, forms a conical bearing serving as the axial bearing for the unit consisting of motor rotor and pump impeller. A further radial bearing is not necessary. The conical bearing keeps the frictional forces small which must be overcome by the motor. This fact ensures, in conjunction with the fact that the motor block, according to the invention, can be easily disassembled and cleaned, the use of a relatively weak, low-noise, inexpensive motor, even when conveying polluted liquids; the starting torque of this motor which is actually weak, particularly in case of one-phase alternating current supply, is still sufficient to ensure safety in operation. Furthermore, after the housing has been opened and the motor block has been lifted off, the unit formed by the motor rotor and the pump impeller can be removed from the axle with one reach, and without requiring the loosening of further screws or other fastening means, in order to visually examine the slot between the motor stator and rotor to find any disturbing foreign bodies present therein, and to remove these foreign bodies, if necessary. When reassembling the assembly, no time-consuming and cumbersome adjustment procedure need to be conducted.

As shown, the pump housing can be provided advantageously with an opening which is normally closed, through which opening the pump impeller can be manually rotated from the outside. This construction makes it possible to free the pump in a simple manner, for example, when the pump is blocked after rather long periods of inoperativeness because of calcium deposits from the conveying liquid or the like, so that the starting torque of the motor is insufficient to initiate the operation of the pump. The control element need only be placed in the closed position in order to separate the pump housing from the fluid cycle. Then, the opening of the pump housing which is normally sealed in a fluid-tight manner by a locking screw, for example, can be opened and a tool, for example, a screw driver, can be inserted through this opening with whose aid the unit formed by the pump impeller and the motor rotor is forcibly turned by hand. This measure can make the disassembly of the motor block superfluous, particularly when the degree of blockage by foreign bodies is rather slight.

According to a modified embodiment of the invention shown, an even more convenient possibility to free the pump is created by making the control element not only rotatable, but additionally externally axially displaceable and connectible with the pump impeller. If the pump is blocked, the control element need only be coupled with the pump impeller, and then the impeller can be freed by turning the control element. The coupling between the control element and the pump impeller can be flush or frictional coupling. A frictional coupling makes it possible to check the direction of rotation of the rotor when the motor is running.

The conveying efficiency of the pump can be improved, as has been discovered, with the other conditions remaining the same, by delimiting the liquid inlet opening in the outer surface of the control element in the effective area of the egress of the impeller by means of guide flanks forming an acute angle with the tangent on the circumference of the control element, and whose outer peripheral spacing is approximately equal to the length of the periphery of the liquid inlet opening of the pump housing.

In order to make it possible to conduct a fine adjustment of the conveying volume of the pump, the liquid inlet opening in the outer surface of the control element is preferably provided with a cross-sectional aperture area

which varies in the direction of the circumference. The change in cross section can be continuous, or in one or several steps.

The stator of the axial motor provided in the motor block housing is, in a further embodiment of the invention, separated from the rotor by a fluid-tight membrane positioned in the dividing plane of the housing. In this manner, the stator carrying the windings through which current is flowing is protected from moisture in a simple manner. Since the membrane is positioned in the air gap of the motor, and this air gap is not to exceed a relatively small maximum value, the thickness of the membrane is limited. In order still to obtain a high mechanical strength and to avoid damage to the membrane by higher fluid pressures which might occur in the pump housing, the membrane is suitably supported on the stator side by an insulating layer, for example, a synthetic resin mass, filling the adjacent space of the stator windings.

It should be understood, of course, that the foregoing disclosure relates to only preferred embodiments of the invention and that it is intended to cover all changes and modifications of the examples of the invention therein chosen for the purposes of the disclosure, which do not constitute departures from the spirit and scope of the invention set forth in the appended claims.

What is claimed is:

1. A controllable liquid conveying assembly for feeding and radially discharging liquid, devoid of stuffing boxes and glands, comprising: a common housing axially divisible into a pump housing (1) and a motor block housing; said pump housing having liquid inlet and outlet openings (32, 33); a control element adjustable externally of the housings for controlling the feeding and discharge of the liquid; the control element (36) provided with sealing elements (50, 51, 52) permitting a fluid-tight sealing of the inlet and outlet openings (32, 33) of the pump housing (1); a pump impeller; and an axial motor having a rotor operatively connected thereto; said motor being mounted in said motor block housing and having a pump-motor shaft axis (15), said motor driving said pump impeller.
2. Liquid conveying assembly according to claim 1, the control element (36) situated coaxially to the pump-motor axis, and provided with a cylindrical outer surface (48) movable to seal the liquid inlet and outlet openings.
3. Liquid conveying assembly according to claim 1, the liquid inlet and outlet openings of the pump housing facing one another diametrically, and means to reverse the direction of flow of the conveying liquid through the pump by turning the control element by 180°.
4. Liquid conveying assembly according to claim 3, the pump housing provided with several openings for feeding and withdrawing the liquid, to cooperate with the control element.
5. Liquid conveying assembly according to claim 1, the motor rotor and the pump impeller forming a unit rotatably and removably mounted on a fixed axle connected with the motor block housing.
6. Liquid conveying assembly according to claim 5, a conical bearing provided as the axial bearing for the unit formed by the motor rotor and the pump impeller.
7. Liquid conveying assembly according to claim 1, the pump housing provided with a normally closed opening, permitting turning of the pump impeller therethrough by hand from the outside.
8. Liquid conveying assembly according to claim 1, the control element axially displaceable from the outside within predetermined limits, and connectible with the pump impeller.
9. Liquid conveying assembly according to claim 3, said outer surface (48) of the control element having a liquid inlet opening delimited in the effective range of the egress of the impeller by guide flanks (54, 55) which form an acute angle with the tangent on the circumference of the control element, and which have an outer peripheral

spacing approximately equal to the peripheral length of the liquid inlet opening of the pump housing.

10. Liquid conveying assembly according to claim 3, the liquid inlet opening in the outer surface of the control element having a cross-sectional area of its aperture, changeable in the direction of its circumference.

11. Liquid conveying assembly according to claim 1, the stator of the axial motor, provided in the motor block housing separated from the motor rotor by a fluid-tight membrane located in the dividing plane of the housing.

12. Liquid conveying assembly according to claim 11, a stator winding chamber, the membrane on the side of the stator supported by an insulating layer filling the neighboring stator winding chamber.

13. Liquid conveying assembly according to claim 1, further comprising a low-pressure side bearing slot cham-

ber and a high-pressure side external rotor chamber; characterized in that the rotor of the axial motor provided with radial channels connected, on the one hand, with the low-pressure side bearing slot chamber and, on the other hand, with the high-pressure side external rotor chamber.
